DEWATERER FOR FLAKED AGAR OR THE LIKE

Filed Dec. 4, 1926

FIG. 1

FIG. 2

Attorney

UNITED STATES PATENT OFFICE.

JOHN BECKER, OF SAN DIEGO, CALIFORNIA, ASSIGNOR TO AMERICAN AGAR COMPANY, OF SAN DIEGO, CALIFORNIA, A CORPORATION OF NEVADA.

DEWATERER FOR FLAKED AGAR OR THE LIKE.

Application filed December 4, 1926. Serial No. 152,715.

My invention relates to a dewatering apparatus, more particularly adapted for dewatering agar in the process of its production, or any other colloidal substances, and the objects of my invention are: first, to provide a flaked agar dewatering apparatus which will efficiently handle such colloidal substances and separate the water from the agar or other colloidal products; second, to provide an apparatus of this class with means for agitating the agar and water when separating the agar from the water by suction means; third, to provide an apparatus of this class in which the water is drawn from the flaked agar through a screen and conducted to a separate reservoir; fourth, to provide an apparatus of this class which is automatic in its action, and fifth, to provide an apparatus of this class which is very simple and economical of construction, durable, efficient in its action, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side elevational view of my dewatering apparatus, showing some of the parts and portions broken away to facilitate the illustration; Fig. 2 is a partial sectional and elevational view of the same at a right angle to that of Fig. 1, and Fig. 3 is a sectional view of the stationary central drum portion of the apparatus.

Like characters of reference refer to similar parts and portions throughout the several views of the drawings.

The trough 1, agitator 2, leg members 3, brackets 4 and 5, stationary drum 6, revolving drum consisting of the side plates 7 and 8, annular outer plate 9, screen 10, tubes 11, inner revolving drum 12, gear 13, pinion 14, pulleys 15 and 16, drive wheel 17, and scraper 18, constitute the principal parts and portions of my dewatering apparatus.

The trough 1 is a semicircularly formed sheet metal trough and is supported on four legs 3. These legs 3 also support the large brackets 4 and 5, which are in spaced relation

and annular in form, forming journals for the member 12 to revolve in. The bracket 5, it will be noted, extends downwardly upon the leg 3 on one side and provides a journal for a shaft 15^a upon which the pinion 14 is mounted and also a pulley 15 and the main drive pulley 17.

Mounted on the lower side of the trough 1 are the journal members 1^a and 1^b in which is revolvably mounted the agitator 2, which is a twisted sheet metal plate, which is shown best in Fig. 2 of the drawings, provided with a shaft portion, which extends through the journal 1^a, and mounted on the end of the shaft extending through the journal 1^a is a pulley 16, operated by means of a belt 16^a extending over the pulley 15, which is on the main shaft 15^a.

Meshing with the pinion 14 is a spur gear 13, which is rigidly secured on the end of the member 12, thus providing means for revolving the member 12 in the journals formed by the brackets 4 and 5. Positioned in the member 12 is a stationary drum member 6, around which the member 12 revolves. This stationary member 6 is held from revolving by means of a bracket 4^a, which is secured to the end of the member 6 and also to the bracket 4.

The drum member 6 is provided on its inner side on one side with an inwardly extending portion 6^a, which is hollow, providing a suction conductor 6^b extending from end to end on the interior of the member 6. It is also provided with a pair of rows of holes 6^c extending from its exterior to its interior, as shown best in Fig. 3.

Mounted on the end of the member 12 is an annular member 12^a by means of bolts 12^b adapted to hold the packing 12^c for forming a tight joint between the members 6 and 12 at the end.

Mounted in the member 12 are a plurality of radiating tubes 11, which are secured thereto by means of lock nuts 11^a. The inner ends of these tubes are in alignment with and adapted to revolve over the holes 6^b in the member 6 with the revolution of the member 12 relative to the member 6. The tubes 11 are provided on their outer ends with flanges 11^b on which is mounted the annular member 9. This annular member 9 is provided with a shaft portion 9^a over which is mounted a screen 10. This screen 10 is adapted to hold the flaked agar, but permits the water to filter through the screen. It has been found that

fine baked Monel metal screen is preferable to fabric for this filtering purpose. The tubes 11 and annular member 9 are enclosed by means of the side plates 7 and 8, which are secured to the member 12 and supported by braces 7^a and 8^a, and their outer edges extend partly past the outer edge of the member 9 and screen 10, forming a drum for the flaked agar to rest against.

- 10   Mounted on the one side of the trough 1 by means of a bracket 18^a is the scraper member 18, which extends past the edge of the trough at one end, and its other end is placed in juxtaposition to the screen, as shown best in Fig. 1 15 of the drawings, adapted to scrape the flaked dewatered agar from the screen and conduct it away from the apparatus.

The operation of the apparatus is as follows:

- 20   Agar with the water is placed in the trough 1. The stationary drum 6 is connected with a suction pump by means of the conductor 6^a, thus providing suction in the interior of the drum 6 at all times. The drum, consisting 25 of the members 7 to 12, inclusive, is revolved by means of the gear 13, pinion 14, shaft 15^a and drive wheel 17. The ends of the tubes 11 pass over the ports 6^c of the member 6. The flaked agar is caused to be drawn against the 30 screen 10 by the suction, the water and agar being thoroughly agitated by means of the agitator 2. The water is drawn from the agar through the screen 10, passes through the tubes 11 into the interior of the drum 6 and 35 out through the conductor 6^b by the suction of the pump, while the flaked agar passes around on the drum and is scraped from the drum by means of the scraper 18 and is conducted away from the apparatus by means 40 of the extended portion of said scraper.

Though I have shown and described a particular construction, combination and ar-

rangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In an apparatus of the class described, a semicircular trough, an agitator revolvably mounted in the lower side thereof, a drum provided with a filter surface revolvably mounted with a portion in said trough, a suction drum provided with a plurality of orifices from its interior to its exterior, a cylindrical member revolvably mounted on said suction drum provided with openings therein adapted to communicate with the openings in said suction drum, and tubes connecting said orifices with the interior surface of said filter surface.

2. In an apparatus of the class described, a semicircular trough, an agitator revolvably mounted in the lower side thereof, a drum provided with a filter surface revolvably mounted with a portion in said trough, a suction drum provided with a plurality of orifices from its interior to its exterior, a cylindrical member revolvably mounted on said suction drum provided with openings therein adapted to communicate with the openings in said suction drum, tubes connecting said orifices with the interior surface of said filter surface, and means for simultaneously revolving said drum and said agitator.

In testimony whereof, I have hereunto set my hand at San Diego, California, this 27th day of November, 1928.

JOHN BECKER.
